UNITED STATES PATENT OFFICE.

KENNER TAYLOR, OF FRANKFORT, KENTUCKY.

NAIL-SEAL.

No. 917,907.

Specification of Letters Patent.

Patented April 13, 1909.

Application filed July 11, 1908. Serial No. 443,039.

To all whom it may concern:

Be it known that I, KENNER TAYLOR, a citizen of the United States, residing at Frankfort, in the county of Franklin and 5 State of Kentucky, have invented certain new and useful Improvements in Nail-Seals, of which the following is a specification.

This invention relates to nail seals.

In the transportation of certain classes of 10 merchandise in packing cases, such, for example, as bottled whisky, it is not uncommon to find that cases have been opened, a portion of the goods removed and the cases restored to their original appearance. That 15 can be easily done when common nails or screws are used in securing the parts of the packing case together; and the object of this invention is to adapt nails to seal up packing cases so securely that they cannot be opened 20 in transit without so mutilating the case that both the common carrier and the consignee may readily see that it has been broken into. This evidence establishes a claim of the consignee against the common carrier for damages, and for loss if there has been pilfering. 25

To this end my invention consists in the construction and combination of parts forming a nail seal, hereinafter more fully described, and particularly pointed out in the 30 claim, reference being had to the accompanying drawings, in which—

Figure 1 represents part of a packing case in vertical section, showing one of my nail seals in service. Fig. 2 shows the seal in 35 vertical section, and a nail in side elevation, ready for the nail to be driven in. Fig. 3 shows a punched blank for making the seal portion of sheet metal. Fig. 4 shows the blank with the toes turned back to thicken those portions and form bosses. Fig. 5 shows a finished seal made of sheet metal. Fig. 6 represents a cross section at line α of Fig. 2.

Numeral 10 represents the common steel wire finishing nail with a small head and 40 wedge-shaped point. As sold on the market such nails are fully adapted for my use.

The body 11, of the seal, is cylindrical and has a bore or opening partly through its 45 length to receive and fit closely upon a nail 50 10, and it flares open at the top to receive the head of the nail. The flange 12, is the

head of the seal. The lower end of the body is parted by slots 13, into a number of legs 14, preferably three, the ends of the legs being turned in to form the inwardly projecting 55 bosses 17.

A portion of the top of a packing case is represented at 16, and the side at 15. In applying the seal, it is first necessary to bore a hole through the top 16, and down into the 60 side 15, to receive the seal very tightly. The seal is to be driven in until its head countersinks into the top 16. Now if the nail be inserted and driven, its point, penetrating between the bosses 17, will spread the legs 14, 65 apart, causing them to bend along the thin portions 18, and forcing their points outward into the wood of the case side 15. This operation is not likely to split the wood, because the leg points are buried below the surface; but if the top were forced off, the wood 70 must be torn to permit the withdrawal of the seal either from the side or top. This tearing of the packing case would prevent its being restored beyond plain detection, and is the 75 safeguard aimed at by this invention. The nail may be somewhat longer than the seal, and its head should be driven in below the surface of the head 12, to prevent getting hold of the head to withdraw the nail. The 80 enlarged head of the common nail prevents its being driven through the seal to free it.

For economy of construction these seals are preferably made of sheet metal. A blank is first to be punched out and slit to form 85 legs, as shown in Fig. 3; then the ends of the legs are to be folded back upon one face as at 20. Then a die having V-shapes to enter the slots between the legs, is to be struck upon this blank, spreading open one face of the 90 slots and giving V-shape to the ends 20, folded over on the legs. Then the blank is to be rolled into cylindrical form and the flange 12, is to be made by a blow from a die, forming the head. It may be enlarged under 95 the head at 19, if required. The finished seal is shown at Fig. 5.

These seals may be made at small cost, and, considering the immunity from pilfering that they would insure, and the annoyance 100 to consignor and consignee that they would prevent, their utility cannot be questioned.

Having thus described my invention, what I believe to be new, and desire to secure by Letters Patent is the following:

In nail seals, a cylindrical seal portion having a flanged head and an opening along its upper portion to receive the body and head of a nail, and parted into legs along its lower portion; the legs having their lower ends

folded back upon themselves, forming inwardly projecting bosses.

In testimony whereof I affix my signature in presence of two witnesses.

KENNER TAYLOR.
